[57] CLAIM

The ornamental design for a beam splice, as shown and described.

DESCRIPTION

FIG. 1 is a perspective view of a beam splice showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view;

FIG. 7 is a bottom plan view thereof;

FIG. 8 is a front perspective view thereof; and,

FIG. 9 is a front perspective view thereof.

The broken line showing of the beam in FIGS. 1,3,4,5,6, and 9 is for illustrative purposes only and forms no part of the claimed design.
